CARD PUNCH AND PRINTER FOR DATA PROCESSING

Charles A. Pycha, Rochester, Minn., assignor to International Business Machines Corporation, Armonk, N.Y.

Filed Apr. 19, 1974, Ser. No. 462,480

Term of patent 14 years

Int. Cl. D14—02

U.S. Cl. D26—5 C

FIG. 1

FIG. 2

FIG. 1 is a right front perspective view of a card punch and printer showing my new design; and

FIG. 2 is a left rear perspective view of said card punch and printer.

I claim:

The ornamental design for a card punch and printer for data processing, as shown.
